UNITED STATES PATENT OFFICE.

CHARLES H. RITSCHER, OF GLEN RIDGE, NEW JERSEY, ASSIGNOR TO THE FIRM OF CAMPBELL, METZGER & JACOBSON, OF NEW YORK, N. Y.

DESIGN FOR A TEXTILE FABRIC.

54,562.

Specification for Design.

Patented Mar. 2, 1920.

Application filed May 1, 1919. Serial No. 294,069. Term of patent 14 years.

To all whom it may concern:

Be it known that I, CHARLES H. RITSCHER, residing at Glen Ridge, in the county of Essex and State of New Jersey, have invented a new, original, and ornamental Design for a Textile Fabric, of which the following is a specification, reference being had to the accompanying drawing, forming part thereof.

The figure is an elevation of part of a textile fabric showing my new design.

I claim:—

The ornamental design for a textile fabric, as shown.

CHAS. H. RITSCHER.
